UNITED STATES PATENT OFFICE.

ALEXANDER S. RAMAGE, OF BUFFALO, NEW YORK, ASSIGNOR TO INTERNATIONAL COLOR & CHEMICAL COMPANY, INCORPORATED, OF DETROIT, MICHIGAN, A CORPORATION OF NEW YORK.

SPRAYING COMPOSITION.

1,166,387.

Specification of Letters Patent. Patented Dec. 28, 1915.

No Drawing.

Application filed April 16, 1915. Serial No. 21,871.

To all whom it may concern:

Be it known that I, ALEXANDER S. RAMAGE, a subject of the King of Great Britain, residing at Buffalo, in the county of Erie and 5 State of New York, have invented certain new and useful Improvements in Spraying Compositions, of which the following is a specification.

This invention relates to spraying compositions for foliage, the object of the invention being to provide a spraying composition which when dry will become practically waterproof or at least unaffected by rain, with the result that the interval between 15 sprayings may be greatly increased and the number of sprayings correspondingly diminished.

The invention will be described by reference to a preferred embodiment thereof, it 20 being understood that it is not limited to the specific materials or proportions hereinafter mentioned as illustrative.

Example: Arsenate of lead, produced in any usual or desired way, is suspended in 25 water, and there is added about ten per cent. by weight, calculated upon the dry arsenate, of a soluble soap, preferably a tallow soap. I then add a dissolved salt of lead, preferably lead acetate or nitrate, in proportion to precipitate the soap in the form of an insoluble 30 lead compound or soap, distributed through and over the arsenate. This operation may be carried out at ordinary temperatures, and the resulting composition may be used at 35 once in the form of a water suspension; or it may be converted into a paste for storage or shipment and re-suspended in water for use.

It is found in practice that a spraying 40 composition prepared as above possesses excellent adhering and weathering qualities, has no corrosive effect upon the foliage, is highly effective as an insecticide, and requires only about one-half of the usual number 45 of sprayings to insure protection. The sodium nitrate which is formed coincidently with the precipitation of the metal soap possesses a certain fertilizing value in so far as it may ultimately reach the plant roots, 50 and is advantageously conserved in the suspension or paste.

Spraying compositions containing Paris green may be similarly prepared, the soap solution being added to the Paris green

while the latter is in aqueous suspension, 55 and the corresponding copper soap precipitated by the addition of an equivalent quantity of copper sulfate. This addition of metallic soaps to copper-containing spraying compositions has a tendency to lessen 60 their known corrosive action on delicate foliage.

Other spraying compositions, as for example, Bordeaux mixture or similar mixtures, may be treated in like manner. The 65 insoluble soap precipitated upon the substance which forms the base of the spraying composition may be a soap of the same metal which enters into this composition, or of another metal, as may be desired, the essential 70 feature of the invention being the precipitation, upon the insecticide substance and coating the particles thereof, of a soap which is insoluble in water and will serve to impart the properties above described. 75

Any of the above compositions containing the requisite proportion of an insoluble metallic soap may be applied to the foliage in the form of a dry or substantially dry powder by a process of blowing. The compositions prepared in accordance with this invention are very advantageously and economically used in this manner, being light and fluffy in character and hence easily carried and distributed by blowing, and at the 80 same time adhering well to the foliage. Furthermore, they are strongly water-repellent owing to their soap-content, and hence are not easily washed off even when they have been applied in powder form. These 85 advantages are particularly strongly marked in the case of Paris green.

A further advantage possessed by the arsenic-containing products prepared in accordance with this invention is that owing 90 to the insolubility of the metallic soap which coats the individual particles, as well as its water-repellent character, any tendency of the arsenic to pass into solution in water is overcome, or very greatly diminished, thereby lessening or entirely avoiding the corrosive effect upon the foliage. 100

I claim:

1. A water-repellent insecticide composition comprising a solid substance having insecticidal properties and an insoluble metallic soap coating the particles thereof. 105
2. A water-repellent insecticide composi-

tion comprising a substantially insoluble metallic salt having insecticidal properties, and an insoluble metallic soap coating the particles thereof.

5 3. A water-repellent insecticide composition comprising a substantially insoluble metallic salt having insecticidal properties, the

particles of said salt coated with an insoluble soap of the same metal.

4. A water-repellent insecticide composition comprising lead arsenate, the particles thereof coated with a lead soap.

In testimony whereof I affix my signature.

ALEXANDER S. RAMAGE.
